UNITED STATES PATENT OFFICE.

ADOLF STEFFEN, OF PITTSBURGH, PENNSYLVANIA, ASSIGNOR TO ADAMS BROS. MANUFACTURING COMPANY, INC., OF PITTSBURGH, PENNSYLVANIA.

DESIGN FOR AN ELECTRIC HEATER.

Application filed August 11, 1925. Serial No. 14,389. Term of patent 7 years.

To all whom it may concern:

Be it known that I, ADOLF STEFFEN, a citizen of the United States of America, residing at Pittsburgh, in the county of Allegheny and State of Pennsylvania, have invented a certain new, original, and ornamental Design for Electric Heaters, of which the following is a specification, reference being had to the accompanying drawing, forming a part hereof.

Figure 1 of the drawings is a view, in

front elevation, of an electric heater, embodying my new design, and, Fig. 2 is a view in side elevation thereof.

I claim:

The ornamental design for an electric heater substantially as shown.

In testimony whereof, I have hereunto subscribed my name this 8th day of August, 1925.

ADOLF STEFFEN.
